UNITED STATES PATENT OFFICE.

ALFRED MORK, OF CHICAGO, ILLINOIS.

METAL SHELVING.

1,282,104.

Specification of Letters Patent. Patented Oct. 22, 1918.

Application filed December 7, 1917. Serial No. 205,947.

To all whom it may concern:

Be it known that I, ALFRED MORK, a citizen of the United States, and a resident of Chicago, in the county of Cook and State of Illinois, have invented certain new and useful Improvements in Metal Shelving, of which the following, when taken in connection with the drawings accompanying and forming a part hereof, is a specification.

10 This invention relates to metal shelving which is suitable for use in stores, factories, shops, and other places for storing goods, merchandise, tools, dies and other articles.

15 The objects of the invention are, primarily to obtain non-inflammable shelving which may be prepared for erection in a shop or factory; shipped in a knocked down condition, and readily erected at the place where the 20 shelving is to be installed.

Further objects are to obtain metal shelving which is presentable in appearance, economical in construction, not liable to break, to be broken or get out of order, and which 25 is suitable for the deposit thereon of articles and things which are easily injured, marred or defaced.

Additional objects are disclosed in this specification and denoted in the claims.

30 In the drawings,

Figure 1, is a top plan view of a short length of a shelving construction embodying the invention.

Fig. 2 is a front elevation.

35 Fig. 3 an end elevation of the construction which is illustrated in Fig. 1.

Fig. 4, is top plan view of a portion of a length of shelving forming a modification of the construction illustrated in Figs. 1, 2, 40 and 3.

Fig. 5 is a perspective of a short shelf and Fig. 6, of a longer shelf than the one illustrated in Fig. 5.

Fig. 7, is an end elevation of a shelf.

45 Fig. 8, is a section on line 8—8 of Fig. 3 viewed in the direction indicated by the arrows.

Fig. 9 is a section on line 9—9 of Fig. 8, viewed in the direction indicated by the 50 arrows.

Fig. 10 is a top plan view of a tie bar forming an element of the construction illustrated and

55 Fig. 11, is a perspective of a short pipe or tube forming an element of said construction.

A reference letter applied to designate a given part indicates said part throughout the several figures of the drawing wherever the same appears.

A, A', represent vertical standards, which preferably consist of metal pipes or tubes, to enable a given weight or quantity of material to resist a crushing strain to better advantage than were said standards made of rods or posts. a represent the feet or base of standards A and are preferably not integral therewith, but attached to said standards by screw threads. B, represent pipes or tubes which slip or slide easily on standards A, and are of suitable length to properly position the shelves (lettered C). D, represent tie bars which connect the standards A to standards A', and E are like tie bars which connect standards A, A and 75 also standards A', A', and F, are like bars which connect the standards of a given row or rows of shelving with an additional row (or rows), standing in spaced relation. The several bars are provided with holes or apertures, d, which fit over the standards A, A' respectively, said holes j not being of sufficient size to permit the pipes or tubing B to extend therethrough.

The shelves C are provided on the front 85 edges thereof with return bends to give a rounded and finished edge, G, thereto. The rounded front edges of said shelves are to permit the placing thereon of dry goods and other articles which are liable to be drawn off from or pushed on to the shelves in a manner which would cause injury thereto, were said shelves made with raw front edges thereto.

Where the shelving is to be erected against 95 or immediately in front of a wall single sets or series of standards A, A' is ordinarily sufficient to support the shelves C and the loads to be carried thereby. Where the shelving is to be erected in rows and not 100 adjacent to a wall a plurality of standards A is preferably employed, and the tie bars E are made of suitable lengths to permit additional holes d, d to be made therein midway of the length thereof to fit over the standard 105 A in the same manner as hereinbefore described.

It will be observed that tie bars E are placed, in installing the shelving, on the standards A, A', and that tie bars D are 110 placed on said standards to rest on the said tie bars E or on shelves interposed between

bars D and E, and that said tie bars E rest on the ends of the short pipes or tubes B.

The shelves C are provided with notches H at the ends thereof, which fit to standards 5 A, and when said shelves are longer than the distance from center to center of adjacent standards A A' and A' A', said shelves are also provided with the recesses h.

By the constructions set forth in the last 10 preceding two paragraphs the shelves rest on and are supported by the tie bars E and extend underneath the tie bars D.

I represent rods which extend through apertures J in the tie bars D. These rods I 15 are placed at the ends of the structure and when desired at intermediate points of the construction.

K, represents a drawer, one or more of which may be inserted to form a part of the 20 construction.

At any point in the structure one or more of the shelves C may be omitted and a determined one of said shelves made of greater width, to obtain a writing desk or table with 25 suitable space above it.

To give an incline to the last named shelf (forming a writing desk or table), short sections of pipe or tubing B' are placed on standard A', additional tie bar D' placed 30 between the standards A, A' above and below the rear end of said shelf as is illustrated in Fig. 3 of the drawings.

The combined length of the pipes or tubings B' B', plus the thickness of the additional shelf M, is substantially the same as 35 the length of the corresponding pipes or tubes B, so that the shelves C above said writing desk or table are substantially horizontal.

To install the device a series of standards A A' provided with feet a are put in position, a row of tubes B is placed thereon a horizontal series of the bars E are placed on said standards to rest on the upper ends 40 of said tubes, and connecting the standards together, a horizontal row or series of shelves are put in place on said tie bars E, and tie bars D are then placed on the standards. Additional pipes or tubes B are then put on 45

to the standards, and additional tie bars E, 50 and the building up of the structure as above set forth is continued until the proper height and number of shelves is obtained. When required, the tie bars F are placed on the standards A A' at a suitable height. 55

When the construction is otherwise completed, the top mountings, L, which in addition to forming an ornamental upper end to the standards A, perform the functions of nuts, are turned into place to rigidly secure all parts of the construction together. 60

The table or desk M may be positioned as desired, in the shelving.

I claim:

1. In metal shelving, the combination of 65 a plurality of rows of standards respectively comprising vertical tubes, a plurality of tubes on each of said standards, a plurality of tie bars on said standards arranged to tie together the several standards in a row, shelves on said tie bars, additional tie bars on said standards arranged to tie the standards in one row to corresponding standards in an adjacent row, tie bars positioned between the adjacent ends of said plurality of tubes, the tubes on said standards being of 70 different lengths to obtain, as desired, horizontal and inclined positions to said shelves, and means to secure said recited tubes and tie bars on said standards. 75

2. In metal shelving, the combination of 80 a plurality of rows of standards respectively comprising vertical tubes, a plurality of tubes on each of said standards, a plurality of tie bars on said standards arranged to tie together the several standards in a row, shelves on said tie bars, tie bars positioned between the adjacent ends of said plurality of tubes, the tubes on said standards being of 85 different lengths to obtain, as desired, horizontal and inclined positions to said shelves, and means to secure said recited tubes and tie bars on said standards. 90

ALFRED MORK.

In the presence of—

CHARLES TURNER BROWN,
J. SCUDDER.
